GRILLE FOR ACCORDIONS

Mario Pancotti, Bronxville, N. Y.

Application September 21, 1950, Serial No. 12,293

Term of patent 14 years

(Cl. D56—1)

To all whom it may concern:

Be it known that I, Mario Pancotti, a citizen of the United States, residing at 1416 Midland Avenue, Bronxville, New York, have invented a new, original, and ornamental Design for a Grille for Accordions, of which the following is a specification, reference being had to the accompanying drawing, forming part thereof, in which:

Fig. 1 is a perspective view of a grille for accordions showing my new design; and

Fig. 2 is a top plan view thereof.

The dotted line disclosure appearing in Fig. 1 of the drawing is for illustrative purposes only.

I claim:

The ornamental design for a grille for accordions, substantially as shown and described.

MARIO PANCOTTI.
